(57) **CLAIM**

The ornamental design for a combined UV sterilizer and wireless charger, as shown and described.

DESCRIPTION

FIG. 1 is a front and top perspective view of a combined UV sterilizer and wireless charger, showing our new design; FIG. 2 is a rear and bottom perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; and, FIG. 8 is a bottom plan view thereof.

The broken lines in the figures illustrate portions of the article that form no part of the claimed design.
